(57) **CLAIM**

The ornamental design for the pot handle, as shown and described.

DESCRIPTION

FIG. 1 is a top view of the pot handle with an attachment pad shown in broken lines and which pad forms no part of the claimed design and shows only environment;

FIG. 2 is a cross section view of the pot handle as viewed from the view in FIG. 1 taken along the 2—2 line of FIG. 1 to show the contour of the curved exterior surface to clarify the shape of the design;

FIG. 3 is a side view of the pot handle with an attachment pad shown in broken lines and which pad forms no part of the claimed design and shows only environment;

FIG. 4 is an opposite side view of the pot handle opposite the side view shown in FIG. 3 with an attachment pad shown in broken lines and which pad forms no part of the claimed design and shows only environment;

FIG. 5 is a bottom view of the pot handle with an attachment pad shown in broken lines and which pad forms no part of the claimed design and shows only environment;

FIG. 6 is a front view of the pot handle with an attachment pad shown in broken lines and which pad forms no part of the claimed design and shows only environment;

FIG. 7 is a rear view of the pot handle with an attachment pad shown in broken lines and which pad forms no part of the claimed design and shows only environment;

FIG. 8 is a bottom perspective view of the pot handle as viewed from the rear with an attachment pad shown in broken lines and which pad forms no part of the claimed design and shows only environment; and,

FIG. 9 is a side perspective view of the pot handle with an attachment pad shown in broken lines and which pad forms no part of the claimed design and shows only environment attached to a cooking pot which is in broken lines. The pot forms no part of the claimed design and shows only environment.

The broken lines showing the portions of a pad to which the pot handle is to be attached and the pot to which the pad is attached are for illustrative purposes only and form no part of the claimed design. The broken lines show environmental structure and is environment only.
